(57) CLAIM

The ornamental design for a jigsaw blade handle as shown and described.

DESCRIPTION

FIG. 1 is a front, top, right side isometric perspective view of a jigsaw blade handle in accordance with my design; FIG. 2 is a front elevation view of the jigsaw blade handle as shown in FIG. 1.

FIG. 3 is a rear elevation view of the jigsaw blade handle as shown in FIG. 1.

FIG. 4 is a left side elevation view of the jigsaw blade handle as shown in FIG. 1.

FIG. 5 is a right side elevation view of the jigsaw blade handle as shown in FIG. 1.

FIG. 6 is a top plan view of the jigsaw blade handle as shown in FIG. 1; and,

FIG. 7 is a bottom plan view of the jigsaw blade handle as shown in FIG. 1.

The broken lines illustrate portions of the jigsaw blade handle which form no part of the claimed design.

1 Claim, 4 Drawing Sheets
